UNITED STATES PATENT OFFICE

GERALD A. FITZGIBBONS, OF ST. LOUIS, MISSOURI

DESIGN FOR A SODALITY PIN

Application filed March 10, 1931. Serial No. 39,014. Term of patent 3½ years.

To all whom it may concern:

Be it known that I, GERALD A. FITZGIBBONS, a citizen of the United States, residing at St. Louis, in the county of St. Louis City and State of Missouri, has invented a new, original, and ornamental Design for Sodality Pin, of which the following is a specification, reference being had to the accompanying drawings, forming part thereof.

Figure 1 is a plan view of the front face of the sodality pin.

Figure 2 is a similar view showing the reverse face, and

Figure 3 is an edge view of the design.

I claim:—

The ornamental design for a sodality pin, as shown.

GERALD A. FITZGIBBONS.
